US00D468377S

(12) **United States Design Patent** (10) Patent No.: **US D468,377 S**
Manville (45) Date of Patent: ** Jan. 7, 2003

- (54) **CRAFT KIT CONSTRUCTION
COMPONENT -
FLAME-AND-BOW HAIR-STYLE FORM**
- (75) Inventor: **Richard B. Manville**, Los Angeles, CA (US)
- (73) Assignee: **Mattel, Inc.**, El Segundo, CA (US)
- (**) Term: **14 Years**

(21) Appl. No.: **29/158,017**(22) Filed: **Mar. 26, 2002**(51) LOC (7) Cl. .... **21-01**(52) U.S. Cl. .... **D21/658; D21/661**(58) Field of Search .... **D21/658, 659, D21/661, 621-649, 594, 593, 490, 492, 493, 497, 502-505, 484, 486, 489, 496, 498, 577, 487, 488; 446/97-101, 268, 319, 321, 337, 387, 372, 394, 77, 83; D11/160, 164; D28/92, 93; D2/865, 866, 869, 875, 895**(56) **References Cited**
